NECKTIE AND COLLAR COMBINATION

Ransom Y. Bovee, Van Nuys, Calif., assignor of
one-fifth to Earl E. Moore, Los Angeles, Calif.

Application January 1, 1945, Serial No. 570,831

10 Claims. (Cl. 2—137)

1

This is an invention for an inter-cooperating necktie, shirt and collar combination, the necktie being either of the four-in-hand variety or of the bow variety, the collar being made in a manner to readily receive the necktie attached either to the neck band or the lapels thereof. The necktie and collar of this invention may be used separately with other kinds and types of collars and neckties respectively, but in view of the fact that this invention is for its principal purpose designed to present neckties and collars that are most comfortable to the wearer and most readily adaptable for use, it is best that the neckties and collars of this invention should be used together.

For many decades, consistent and repeated attempts have been made by numerous inventors and manufacturers to produce a quickly attachable ready-tied necktie to avoid the nuisance of hand-tying, as this generally results in early tearing, raveling and general destruction of the necktie. It is well known why all ready-tied neckties have been a failure. Foremost, the most publicized reason is that they frequently fall off and thus cause great embarrassment to the wearer. No ready-tied tie has duplicated the neatness or the appearance of the present hand-tied tie. Further, construction details and lack of practical features to keep them properly positioned and properly secured has been an impediment toward the sales of such ties. The permaform tie and companion collar of this invention overcome all the above objections and goes far beyond in the accomplishment of a practical combination of a shirt-collar and companion tie structure which affords perfect neck comfort, perfect tie appearance, and perfect collar appearance.

The necktie of this invention is provided with an elastic band as the resilient means for holding the tie in position, hooks being provided at the ends of the elastic and arranged for gripping pockets or loops in either the upstanding neck-band portion of the collar or at the inner portion of the flaps of the collar. By utilizing an elastic which does not encircle the wearer's neck, there is no gathering or bunching along the neck-band, thus the wearer is much more comfortable with a tie device of the type set forth in this application. The necktie is provided with a pre-designed form onto which the necktie is wrapped or draped, and means are provided within the form to accommodate the elastic; the elastic, however, not being fixed to the form so that the form and its tie are free to be shifted or slipped along

2

the elastic for readily adjusting itself between the front flaps of the collar.

The collar is made of three substantially identical pieces of suitable goods, the ends or front flaps thereof being reenforced with a gusset piece which provides a strong and permanent means to receive the hooks of the elastic. The hooks are attached to the elastic in a special manner so that the open portions of the hooks will always be in a suitable gripping position for readily engaging the pockets when glided along the surface of the collar band or along the inner surface of the collar flaps.

The collar of this invention is designed and arranged to give maximum comfort to the wearer thereof, to make it easy to adjust, and economical to make, and also to save collar bands from wear.

One of the principal objects of this invention is to present a new and novel necktie and collar combination that is conventional in appearance, sturdy and neat in construction, dependable for giving a neat and dressed appearance, which is easy to arrange and adjust, and adapted for instant attachment and detachment without injury to either collar or necktie.

Another object is to provide a necktie with a pre-designed form having means to allow an elastic to slip therethrough so that it can be self-adjusting at the front of a collar.

Another object is to provide a design and construction of a shirt collar whereby the usual separately made neck-band and collar may be combined in one flat structure, and be adapted to provide engaging means for a permaform necktie either on the shirt neck-band portion or upon the integral lapel-collar portion of the structure.

Another object is to provide a collar with less parts and less sewing, easier to iron and requiring no starch.

Another object is to provide a simple style-formed collar that is easy to make and which is provided with means for co-acting with a necktie unit, such a construction being provided to allow for durable and dependable securement of a readily removable preformed necktie in combination with a soft-shirt collar, the tie being readily attached to the front part of the collar so as to be free of choking bands which pass around the neck.

Another object is to provide a shirt collar constructed in such a manner that hook engaging pockets are formed in the collar material on the neck band or under the collar lapels by which a preformed necktie with mating hooks can be

engaged for supporting the tie, and the provision of reenforcement means at the lapels of the collar to prevent their curling at the tips.

Another object is to provide a pre-formed necktie engaging means in the goods of a soft collar which means acts as a collar lapel reenforcement to prevent curling and also acts to provide hook engaging pockets selectively either under the lapels or upon the neckband of the collar for engaging hook attaching types of neckties.

Another object is to provide a soft shirt and collar having a method of construction which permits the collar and collar band to be combined in one piece and folded in a manner for combining lapel and neckband reenforcements and stiffener lining that are all sewed together with hook engaging pockets sewed in the reinforcements to appear on the underside of the collar lapels or flaps and on the frontal side of the neckband as an invisible means for securing a hook-on type of necktie.

Another object is to provide a fold-over soft shirt collar and neckband with hook pockets formed in the reinforcements fronting the fold-over collar lapels and the neckband buttoning extremities so that the reenforcement pieces and the pocket lapel stiffeners may be sewed outside to form the pockets and through the goods and collar lining on the opposite side and then with an additional collar and neckband piece of goods placed over the reinforcement so as to cover the pockets already formed, then sewed all around into a complete collar. When this is turned inside out, the stiffening lining is on the inside and the hooking-pocket reenforcers are on the outside in the flat but with the collar folded over in wearing position, and thus the hook-pockets are under the lapels and on the frontal outside extremities of the buttoning ends of the formed collar band.

Another object is to provide such a collar so that a hook engaging necktie can be secured either to the lapels of the collar to hold them neatly together against the necktie or to provide hook anchorages likewise in the outwardly engageable pockets in the buttoning ends of the formed collar band so that elastic with its secured hooks passing through the knot end of the tie can be quickly and securely engaged therein or disengaged instantly.

Still another object is to present the combination of a special made soft collar and a permanent formed necktie to be worn therewith, the collar being made in a manner that less material and labor is required than with the usual collar and tie. The tie is formed so as to bring into prominence artistic designs exactly in the ideal position in the knot or upon the tail portion of the tie.

Other objects, advantages and features of my invention will appear from the accompanying drawings, the subjoined detailed description, the preamble of these specifications and the appended claims.

Applicant now presents the following illustrations and detailed specifications of one or more forms of his invention in order to teach one the art as to how to make and use the same, but it is to be understood that the drawings and the description thereof are not intended to limit the scope of the invention in any sense whatever except as the invention is limited expressly by the appended claims.

In the drawings:

Fig. 1 is a front elevational view of a necktie and collar combination with the necktie attached

to the collar-band in typical wearing relationship thereto, and showing the elastic with its connected attaching hooks beneath the lapels of the collar as they engage in holding relationship the hook-pockets underneath the lapels, parts of the collar being broken away in order to better show the collar and tie relationship.

Fig. 2 is a side cut-away elevational view showing the forward pitch given the knot of the tie so as to project it beyond and through the lapels of the collar and thus give it prominence and prevent it from hanging flat and limp, thus showing the effect of the elastic draw upon the hooks as they snugly hold and retain the necktie in proper wearing position in relationship to the collar.

Fig. 3 is a rear elevational view of the knot portion of the tie, showing the sewing seams thereof.

Fig. 4 is a rear elevational view of the necktie knot-former per se and shows the slot means for assembling the elastic therein; the slot also permitting the reversing of the direction in which the hooks face after the necktie is assembled thereto.

Fig. 5 is a top plan view showing the kick-over effect of the elastic against the holding hooks which gives them slide-in resistance and proper angulation for easy hooking engagement, also shows how the elastic pressure at the base of the knot-former projects the necktie outward and downward for prominent wearing effect.

Fig. 6 is a side elevation of necktie knot-former at its wearing angle and is shown beneath a strip of tie material before it is applied to the knot-former.

Fig. 7 is a top view of the elastic necktie holder fixed to a pair of compression-grip collar-engaging hooks, showing the extended kick-over projection at the back of the compression-grip and end-stop rear position of the hooks, and further shows the comparative shortness of the elastic to provide assembly tension when assembled in the necktie holder and knot-former.

Fig. 8 is a rear elevational view of a bowtie.

Fig. 9 is a top plan view of the bow tie former showing the center bulge which secures the tie from slipping off; the attaching hooks in this view are shown as turned forward for engaging the lapel hook pockets as the bow is generally worn on the outside of the lapels and they are thus held together beneath the bow tie.

Fig. 10 is a plan view of one of the pieces of goods used to form a bow.

Fig. 10a is a plan view of the goods used to cover the knot of the tie core.

Fig. 11 is a plan view of a portion of a collar.

Fig. 11a is a plan view of portion of a more completed collar.

Fig. 12 is an elevational view of a portion of a collar attached to the upper portion of a man's shirt.

Fig. 13 is a plan view of a portion of a collar in completed form, and

Fig. 14 is a plan view of a reenforcer portion of a collar.

The four-in-hand necktie 1 illustrated in Figs. 1, 2, 3 and 6 of the drawings is shown in combination with the soft collar 2 of a man's shirt. The tie has the usual lower section or tail section 1', which is generally of the double tail variety, and the central portion 3 which in ordinary ties is the middle portion thereof that passes around the neck band of the collar. In this invention, however, the portion 3 is just a short extended

part of the tail of the tie for the reason that the usual long tie having the double tails is not needed. In order to give the tie the appearance of the ordinary knotted four-in-hand tie, the tie is given a slight fold as shown at 4, Fig. 6, and then sewed underneath to maintain the fold. The fold, when placed upon the knot-form fixture or core 6, is alined with the bottom edge of the knot-form and the upper section 5 of the tie is folded over the top of the knot-form and down along the rear thereof. The knot-form or fixture 6 is the core of the tie and its style may be of any shape or type to suit the fad of the season.

The knot-form 6 has a front concaved surface 7, a rear concaved surface 8, and neatly formed side surfaces 9 and 10 to conform with the intended artistic design of the tie. The necktie is affixed to the tie form 6 in the following preferred manner: the fold or crease 4 is placed over the front of the form so that the fold is just even with the bottom edge of the knot-form which has been designated as 6'. The upper portion 5 is draped over the top 7' and tucked around the rear portion 8 of the knot-form. Then the side edges of portion 5 are snugly pressed around the knot-form and overlap the rear portion and end 3' of the tie, then the just mentioned portions are sewed together along the lines a, b and c to form a perfect and permanent tight knot.

At the upper portion of the knot-form is an integral slip channel 11 having an open sided slot 12, the channel accommodating an elastic band or tape 13 which may be made of rubber or of any suitable resilient material. The elastic is not attached to the sides of the channel, therefore the elastic is always free to shift within the channel; the elastic, however, is prevented from leaving the channel by the end hook or fastener members 14 and 15.

The fastener members 14 and 15 are alike and are arranged and configurated, as shown, for permanently clamping the elastic between the overlapping portions 16 and 17 which may have their opposed surfaces roughened or spiked for firmly gripping and holding the elastic; this obviously would be done by machine so that the clamping members will tightly and positively squeeze and hold onto the elastic. The curved portion 17 has an extended portion 18 which bends into the form of a catch or hook 19. Note, in particular, that the portion 16 extends a little beyond the end of bend 17', and note the position of the member 14 (or 15) as it leans or slants toward the pocket of the collar to which it is to be engaged. It is the extension of portion 16 which causes the hook member to pitch forward toward the pockets so that the hooks will readily grab or hook any suitable pocket or band into which it is capable of anchoring. This latter feature is very important in that it makes it easier for a person to attach the necktie to the pockets which are provided in the collar structure. When the necktie is once anchored to the pockets of the collar it cannot slip out because of the tension of the elastic, but the knot can, however, be adjusted since the elastic is not attached to the channel 11 and this feature makes it very easy to shift the knot from side to side into proper position. Because of the action of the collar lapels or flaps against the sides of the knot, the knot tends to adjust itself to proper position, a very important feature.

The bowtie of Fig. 8 has substantially the same core elements as the four-in-hand tie and this is true especially with the elastic and the end hooks

as these parts have been given the same reference characters. The bowtie is indicated by the numeral 20 and this tie has the usual double flaps or wings 21 and 22 and the central knot part 23 with the ends thereof sewed together at 24. Note, however, that the hooks 14 and 15 are clamped to the elastic so that the openings of the hooks face the band of the collar. It is also intended that the openings of the hooks face the flaps of the collar in some instances as it has been discovered that when the hooks are attached to the pockets in the collar lapels or flaps, the elastic pulls the flaps toward each other and makes them hug the knot of the necktie, a feature desired by many tie wearers.

The knot portion along the lines 30 of the bowtie is wrapped about a knot-form or core 25 which has the open slot 26, and this knot-form is not fastened to the elastic, but is the same as in the preferred form of the invention, so that the knot-form can be easily shifted therealong for the purpose of centering the bowtie with respect to the collar flaps. The bulged or rounded portion 25' is provided on the knot-form or core to prevent the tie goods from slipping off the form or core 25.

Fig. 10 shows the goods of the bowtie before being wrapped about the core 25. The goods is just a strip of suitable material 27 with its ends 28 and 29 folded along the lines 28' and 29' to substantially meet at 30. Stitches 31 are provided along both edges as shown, and then the material is turned inside out and applied to the core 25 by merely pressing the central portion 30 about the knot core and then applying the strip 27 and sewing it at 24. Two such center gathered pieces of goods 27 should be used together to give the best effect, that is, one in front of the other to resemble a hand tied bat-wing tie.

The knot-forms in either form of the invention may be made of any suitable material, such as, for instance: wood, hard rubber, light metals, and any one of a great variety of plastics which are now popular for all kinds of small articles. The well known plastics called "Lucite" and "Plexiglass" would be very satisfactory.

The collar, in this particular adaptation of the invention, is indicated at 32. The collar is made of three similar sheets of goods 33, 34 and 35, and the two substantially identical reenforcement elements or reenforcers 36 and 37. The sheet 33 may be called the exposed layer of attractive goods in that this layer is seen when the collar is worn; the sheet 34 may be called the liner in that this one lies between two sheets and is made of stiffer and heavier goods for it is generally the supporting frame work of the collar; and the sheet 35 may be called the under-layer or the folded under-layer in that it is not seen when the collar is worn.

The first step in forming the collar is to lay the liner or stiffener 34 upon the table, note Fig. 11, and then lay the under-layer 35 over the liner in the position shown. At each end of the collar is positioned the reenforcers 36 and 37, these reenforcers being laid over the under-layer, but having their respective edges 38 turned under toward the under-layer. The reenforcers, along with the liner and under-layer, are then sewed together along the dotted line 39 to form the hook pockets 40 and 41 in each reenforcer. Then this assembly is sewed along the fold indicated by the dotted line 42. The bottom 43 is then hemmed under as shown. These stitches which

have thus been made will not show when the collar is reversed, that is, turned inside-out. By this operation, the hook pockets are formed which take the pull of the necktie elastic and distribute its effect so as not to draw, wrinkle or distort the showy front exposed portion of the completed collar.

After the above work is done, the exposed or seen portion 33 of the collar is laid over the assembly shown in Fig. 11; now note Fig. 11a. This new assembly is then stitched all around the edges indicated by the dotted lines 44, 45 and 46, the bottom being left unstitched to allow the entire assembly to be reversed. Note that in Fig. 11a the lining 34 is still on the bottom, but that the under-layer and the reenforcers are sandwiched between the liner and the exposed outer sheet 33. The bottom portion 47 of the frontal exposed sheet is not hemmed under for it is this part of the collar that is sewed first to the top of the shirt then reversed to bring raw edge inside before sewing down the hemmed edge 43 to the outer side of the neck opening.

The collar shown in Fig. 11a is next turned inside-out, this being shown in Fig. 13; note now that the outer frontal exposed sheet 33 of the collar is now on the bottom, the under-layer 35 on the top, and the liner 34 sandwiched between the under-layer and the frontal exposed sheet, and the reenforcers 36 and 37 are on the very top at their respective collar ends. The collar is then pressed and then oversewed along the edges. The collar is then attached, by sewing, to the periphery 48 of the neck opening in the shirt 49, note Fig. 12. The collar is shown with the usual bottom 50 for receiving the bottom hole, not shown, at the other end portion of the collar.

Having thus described my invention, what is claimed as new and desired to be secured by Letters Patent is:

1. In a hook attaching necktie and a shirt-collar, the collar having an integral neck-band portion and a fold-over skirt portion, means adjacent the end extremities of the neck-band for engaging a hook fastening necktie, means adjacent the underfold end extremities of the skirt of the collar for a hook fastening necktie, the said means comprising substantially hook-point pockets sewed into an overlaid edge of collar material goods extending from the bottom of the collar to and along the lapels of the skirt and also to its folded over bottom extremity, the same being adapted to receive and secure fastening hooks to which a preformed necktie is resiliently attached.

2. In a cooperative combination, a shirt-collar with a neck-band portion, a fold-over skirted portion of the collar and neckband both having means adjacent their end extremities for receiving necktie attaching hooks in pockets formed therein, a hook attaching necktie with cooperating hooks compressed upon a resilient band for supporting a necktie, a necktie knot mounting fixture through which the resilient band slidably extends, stops on the hooks to restrain the hooks from entering the mounting fixture, a heel on the hooks to heel them over under elastic tension to make them engage pockets freely, and a necktie sewed on the mounting around the resilient band between the hooks and fixture, and over and around the mounting fixture in a manner to give the appearance of a hand tied tie.

3. In a cooperating combination of a necktie unit and a shirt collar, the collar having a com-

bined neck-band and a fold-over skirt with lapels and having inbuilt means within the goods of the collar to receive and secure necktie hooks both upon the neck-band and upon the lapels thereof, the necktie having resilient hook attaching means adapted to be secured to the said collar upon the selected said inbuilt means thereof by reversing the resilient hook attaching means within the knot portion of the necktie when necessary, so that the necktie may be worn attached to the collar neckband as well as to the lapels and thus to hold them together.

4. In a combination, a quick attaching pre-formed necktie and a hook-pocket necktie attaching collar adapted to receive hooks adjacent the ends of the neck-band and under the skirted lapels thereof, a preformed necktie secured to a necktie knot-forming fixture, a channel extending through the fixture, a resilient band extending through the channel and secured to hooks at each extremity thereof, said hooks having stop shoulders to prevent them entering the channel by the tension of the resilient band, a compression grip fold in the hooks to engage and hold the resilient band, said stop shoulders on the hooks designed to lean the hooks over for easy catch engagement in the hook-pockets of the collar, and an angle projecting heel upon the knot forming fixture to rest against the front of the collar to project the necktie outward and downward under the attached tension of the resilient band.

5. In a knot-former unit for neckties and the like, the knot-former unit having a pre-designed shape with a vertical bowed portion having a cross member along the top thereof, a channel in the rear of the cross member having an elastic strip means with hooks fixed to the ends thereof for attaching the knot-former unit to a collar, said channel having an open slot longitudinally thereof for passage of the strip means when it is placed into the channel.

6. The knot-former unit recited in claim 5 wherein the knot-former unit has attached thereto the upper end of a tie-strip, the tie-strip having its upper end folded over the top of the unit and portions of its side edges folded around the front portion of the unit, the side edges of the upper portion of the tie-strip and the upper end thereof being secured at the rear of the knot-former unit, and a cross-fold in the tie-strip at the point near the lower end of the unit to simulate the bottom edge of the knot of a four-in-hand tie.

7. A bow tie comprising an elongated block with a channel therein, an elastic band in the channel with hooks fixed to the ends thereof, a rectangular piece of material having its middle portion pressed around the block to provide extended wings beyond the ends of the block which conceal the hooks at the front thereof, and a strip of material wrapped around the portion of the rectangular piece which is pressed around the block, the rear ends of the strip having means to firmly hold the entire tie to the block.

8. In combination, a tie-attaching shirt type of collar and a quick attachable preformed necktie fixture, a collar comprising an integral neckband and a foldover skirt portion with hook pockets sewed in the goods under the skirt lapels so that the necktie fixture can be hooked under the lapels to hold them together, collar engaging necktie hooks secured to an elastic band which passes through the necktie fixture, said fixture having a channel therethrough sized to accommodate the

band but preventing the hooks from passing therethrough, but the channel permitting the elastic band to rotate in the channel in order to face the hooks in an outward and forward position.

9. In a necktie unit comprising a rigid necktie mounting fixture with a channel through a rear portion thereof, an elastic band with end fastening means and having its central portion in the channel, the band being unattached to the fixture and thus free to be shifted in the channel, an open slot along the rear of the channel for permitting the elastic band to be inserted into the channel and removed therefrom, the fixture including a projected knot former which extends forwardly to give conspicuous prominence thereto when dressed with necktie material.

10. In combination, a ready formed necktie unit and a collar with means for attaching them together, the means including an elastic extension on each side of the tie unit with a central portion thereof attached to the unit but free to shift therein, a collar having front flaps with a small pocket formed of collar material and positioned

on the underside of each flap, an opening for each pocket facing away from the forwardmost portion of the collar, and a hooking means fixed to each end of the elastic and removably attached to the said pockets.

RANSOM Y. BOVEE.
